UNITED STATES PATENT OFFICE.

EDWIN F. GUTH, OF ST. LOUIS, MISSOURI.

GLOBE HOLDER.

Application filed November 18, 1926. Serial No. 149,066.

My invention relates to the lighting fixture art and particularly to devices adapted to receive and support in position, a globe to surround the light source.

5 The object of my invention is to provide a device for this purpose, of simple, strong, durable and practically inexpensive construction, which may be quickly and easily operated and always dependable to perform the 10 function for which it is designed.

My invention consists of certain details of construction hereinafter set forth, pointed out in my claims, and illustrated in the accompanying drawings, in which

15 Fig. 1 shows an exploded view of my device and a globe to be received thereby;

Fig. 2 shows a sectional view of my device and a part of a globe supported thereby;

Fig. 3 shows a transverse sectional view of 20 the same;

Fig. 4 shows a side elevation view, in detail, of my locking ring;

Fig. 5 shows a side elevation view, in detail, of the canopy terminating in the 25 supporting ring I employ; and

Fig. 6 shows a modification of my locking ring in which I employ a spring, wire shaped, to function in substantially the same manner as the locking ring shown in detail in Fig. 4.

30 As illustrated in the drawings, my improved globe holder comprises a canopy 10, which is supported at its upper extremity by a chain 11 in the ordinary manner. This canopy 10 is of the standard shape, and flares

35 downwardly and outwardly, terminating at its lower end in a vertical cylindrical portion 12 having a bead at its extremity. As far as this construction is concerned, my canopy differs very little from many canopies in general use, it being my desire to utilize the standard form of canopy in constructing my globe holder.

To this end, I punch or stamp one or more tongues out of the vertical cylindrical wall of the portion 12, as indicated at 40 13, and force the punched-out portion 14 inwardly and downwardly to form the tongues 15. These tongues 15 are preferably curved to conform to the curvature of the lip of the globe 17, and should be only on one-half of

45 the circumference of the vertical cylindrical portion 12 of the canopy 10, so as to permit the insertion of the globe 17 in the manner indicated in Fig. 1. I form a plurality of apertures 18 in the vertical cylindrical wall 12, on that side of the canopy 10 opposite 50 the resilient tongues 15. The globe 17 is

locked in the canopy 10 by means of the ring 19, which is formed to telescope the outside of the vertical cylindrical portion 12 and extend down until it contacts with the bead at 60 the lower edge of the canopy 10. I provide a plurality of internally extending lugs 20 on the inner wall of this ring 19, which are located so as to register with the openings 18 in the vertical cylindrical wall 12, and are 65 also curved to correspond to the curvature of the lip of the globe 17.

In my modified form, illustrated in Fig. 6, I construct my locking ring of a heavy spring wire 22, the ends terminating in inwardly 70 extending curved hook members 23, designed to project through their respective openings 18 and engage the lip 16 of the globe 17. By this construction, the locking ring of my device may be applied without inserting it over 75 the canopy as the fixture is being installed, for the spring wire may be forced open to pass across the enlarged central portion of the flanged ring 12 after all the other parts, including the globe, have been placed in their 80 final positions.

In practical operation, the globe 17 is tilted sidewise, as shown in Fig. 1, and the lip thereof placed above the lugs 15. The globe is then moved into its normal position within 85 the ring 12. The locking ring 19 is then brought down, the lugs 20 passing through their respective openings 18, snapping over and engaging below the lip 16 of the globe 17, at points opposite to the lugs 15. The locking 90 ring 19 is then forced downwardly, over the wall of the flanged ring 12 and by friction, and the resiliency of the metal furnishing a spring tension on the tongue, the globe is held firmly in position, locking the assembled 95 parts of my device in their proper functioning position. When it is desired to remove the globe 17, this is accomplished by the operator placing his thumb, or fingers, against the outwardly extending lug 21 and lifting 100 on it, which operates to snap the ring 19 out of engagement with the vertical cylindrical wall 12, and by tilting the globe 17, as shown in Fig. 1, it can be detached from the resilient 105 tongues 15.

It is not essential the supporting lugs be formed by cutting and punching the metal as I have described, but I prefer such, and therefore do not desire to be limited in the scope of my protection except as outlined in 110 the appended claims.

Having thus described my invention what

I claim and desire to secure by Letters Patent of the United States is:

1. A holder for lighting globes comprising a canopy having a vertical cylindrical portion, a plurality of inwardly extending arcuate tongues struck out of said portion, there being an opening in said portion equidistant from said tongues, a securing ring which fits over said vertical cylindrical portion, a similar tongue formed thereon, said tongue fitting said opening.

2. A support for globes, comprising a canopy having a plurality of openings formed in its wall adjacent its lower edge, an inwardly extending resilient tongue formed on the wall of said canopy adjacent its lower edge, a ring adapted to telescope the outer wall of said canopy, inwardly extending resilient tongues on said ring which register with said openings, said tongues being adapted to project inside of the canopy and engage the lip of a globe.

3. A support for globes, comprising a canopy having a plurality of openings formed in its wall adjacent its lower edge, resilient means on the inner wall of said canopy adapted to engage the lip of a globe, a ring adapted to telescope the outer wall of said canopy, and resilient means on the inner wall of said ring adapted to register with said openings and engage the lip of the globe to be supported.

4. A support for globes, comprising a canopy having a plurality of openings formed in its wall adjacent its lower edge, resilient means on the inner wall of said canopy adapted to engage the lip of a globe, a ring adapted to telescope the outer wall of said canopy, and resilient means on the inner wall of said ring adapted to register with said openings and engage the lip of the globe to be supported, said means conforming to the curvature of the lip of said globe.

EDWIN F. GUTH.
